UNITED STATES PATENT OFFICE.

HUGO TOCKHORN, OF BERLIN-TEMPELHOF, GERMANY.

ADDRESSING DEVICE FOR PRINTING PRESSES FOR PRINTING OF FIXED TEXT WITH CHANGEABLE ADDRESS.

Application filed March 17, 1927. Serial No. 176,178.

This invention relates to an addressing device for printing presses for printing a permanent or fixed text with changeable address.

5 One of the main characteristic features of the invention is, that the guide path for advancing the address printing plates to the printing surface is arranged laterally of the printing surface close to the upper end of 10 the same in such a manner, that the address printing plates coming from the container for said plates, slip down into printing position under the action of gravity. So the address printing plates slip from above down- 15 wards along one side of the printing surface so that, under the action of gravity, they not only advance into printing position but also away from that position. The printing lines, in the permanent text of the type 20 chase as well as on the address printing plates, extend from below upward.

Each address printing plate slipped down to the printing position is held, according to the present invention, by a movable stop 25 which releases the plate after the printing so that it then slides under the action of gravity, eventually with the assistance of a shaking movement, to a receiver in a guide inclined in a rearward direction. 30 In order to prevent several consecutive address printing plates arriving at the same time in the printing position, whereby disturbances may be caused, this being an inconvenience of which most of the commonly 35 used printing presses for the simultaneous printing of fixed text and changeable address suffer, a projection is preferably arranged, according to the present invention, at the outlet end of the guide path of the container 40 for delivering the address printing plates, said guide path being inclined in forward and downward directions. The plates are lifted one after the other over the said projection by means of a nose, hook or other kind of lifter, which is raised and lowered 45 by the press actuating mechanism.

One embodiment of the present invention is shown, by way of example, in the accompanying drawings in which:—

50 Fig. 1 shows the general arrangement of the address printing device, according to the present invention, mounted on a press of usual construction which may be mechanically driven.

55 Fig. 2 shows on a larger scale, partly in

side elevation and partly in section, the mechanism for feeding the address printing plates to printing position and for guiding the same away from this point.

Fig. 3 shows on the same scale as Fig. 2 60 a front elevation of the guide path for the address printing plates situated in the printing surface.

Figs. 4 and 5 show, on a still larger scale and in two different working positions, the 65 mechanism for feeding the address printing plates separately into the guide path of the printing surface.

Fig. 6 shows in side elevation a detail view of a coupling device in a position of use 70 different from that shown in Fig. 2.

Fig. 7 shows in front elevation one of the address printing plates.

Fig. 8 is a perspective detail view of the coupling lever shown in Fig. 6. 75

The platen printing press, which may be of any well known construction, is illustrated in Fig. 1 in perspective view merely by representation of its principal parts.

1 is the base or foot of the press, and 2 80 is the platen; 3 are the guide rails for the inking rollers 6, 4 is the type chase, 5 the colour or ink pad, 7 the driving wheel, 8 the fly wheel and 9 the main driving shaft of the printing press. All the above mentioned elements may be constructed in any other convenient manner than that which is illustrated here, or they may be substituted by other suitable elements, as the printing press as such does not form part of the pres- 85 ent invention. 90

On the one side edge of the type chase 4 the device for printing from the address printing plates is arranged. It essentially consists of a guide path 10 extending in the 95 plane of the type chase from above downward. On this guide path 10 the printing point or position 11 for the address printing plates 12 is arranged, one of said address printing plates being shown in Fig. 7. 100

The guide path 10 is formed by two parallel bars between which the address printing plates 12 may slip down. These two bars are connected the one with the other by a rear plate 13 (Fig. 3) or the like, which 105 has hook-shaped lateral extensions 14 engaging studs or screws 15 fixed in the type chase. The guide path 10 with all the elements directly connected to the same may thus be easily removed from the type chase 110

so that the machine can also be used without the address printing device, i. e. only for printing a permanent or fixed text. In this case it is merely necessary to insert a 6 chase of larger size instead of that bearing the guide path 10, and it will then be possible to utilize the entire space which is at disposal for the printing of the permanent or fixed text, for instance when the rear side 10 of a sheet of letter paper has to be printed with such a text.

The container for the address printing plates 12 is formed by a guide path 16 upwardly inclined in rearward direction (Fig. 16 2). In this path 16 a slide 17 is mounted, a stud 18 of said slide projecting through a longitudinal slot in the bottom plate of the guide path 16. A pull cord 19 is attached to the stud 18, and this cord 19 slides over an 20 idler 20 rotatably mounted on the press frame. The other end of cord 19 is wound around a spring barrel 22 which latter may be wound up by means of a key 21, said spring barrel 22 being rotatably mounted on 25 an arm 23 of the press frame. By the spring barrel 22 and the pull cord 19 the slide 17 is permanently pulled as far as possible forward in the guide path 16, the address printing plates 12 in front of said slide 17 being 30 thus pressed against the front outlet end of guide path 16.

On this front outlet end of the container or guide path 16 a projection 24 (Fig. 2, 4 and 5) is arranged at its bottom plate, the 35 lower edge of the foremost address printing plate 12 bearing against said projection. In order to lift the address printing plates 12 separately one after the other over this projection 24 so that they may drop into the 40 guide path 10 leading to the printing position or point, a hook or nose 25 is arranged which is adapted to be moved to-and-fro in a vertical direction. This hook 25 is arranged on the upper end of a rod or arm 26, the lower end of which is raised and lowered from the driving mechanism of the machine in a manner which will hereinafter be more fully described. When the hook 25 is ascending it lifts the foremost address 45 printing plate 12 over the projection 24 at the front end of the container 16, as shown in Figs. 4 and 5. When the hook 24 descends again with the rod 26 the address printing plate 12, which has been just lifted 50 above the projection 24, slides over a curved portion 27 of the projection 24 so that it is separated from the hook 25 and can freely slide into the downwardly directed guide path 10 as indicated in Fig. 2 in dash lines. 55 A roller 28 in the upper end of the path 10 serves to prevent the top end of the dropping address printing plate 12 from toppling forward.

That address printing plate 12, which in 60 this manner has been brought into the guide

path 10, slides under the action of its own gravity down this guide path 10 until it arrives in front of a solid support 11 which serves to support the address printing plate during printing. This address printing plate 12 is held in this position by two movable stops 29 (Figs. 2 and 3) keyed on a common shaft 30, said shaft being journaled in the frame of the guide path 10. A spring 32 is attached to an arm 31 of the shaft 30, the other end of said spring being fixed to the frame of the guide path 10, said spring having the tendency to hold the stops 29 permanently in such a position that they serve as abutments for the address printing plate 12 in the printing position and support said plate from below (Fig. 2).

The stops 29 have rearwardly and backwardly extending arms 33 of such a shape that these arms 33 will be oscillated in forward direction by a projection 34 of rod 26 when this rod is ascending. By the rotation of shaft 30, which is thus produced, the stops 29 in the guide path 10 are turned backwards and liberate the address printing plate 12, which has rested upon said stops up to this moment. The tops of stops 29 are yet slightly raised in this turning movement and therefore correspondingly raise or rock the plate 12 resting upon them, the adhesion between this plate and the support 11 being suppressed thereby. If desired support 11 may be arranged to be able to make itself a slight rocking or backward movement for attaining the same purpose.

The plate 12 freed from the stops 29 will then slide down under the action of its own gravity in the guide path 10. The lower end 35 of this guide path is bent in rearward direction. Below this lower end 35 the receiving container for the address printing plates is to be arranged, which is not shown in the drawing and into which the plates slip from the guide path 10.

The up and down movement of rod 26 and at the same time the to-and-fro movement of the stops 29, is controlled by the following mechanism:

On the main driving shaft 9 of the printing press an arm 36 (Fig. 2) is fixed which carries on the upper side a roller 37 pushing at every turn of arm 36 against a roller 40 mounted on the lower end of an arm 38 of a bell-crank lever pivotally arranged by means of a shaft 39 at the press frame. The other arm 41 of this bell-crank lever is tapered or stepped at its free end 42 (Fig. 8). Beside arm 41 an arm 43 is arranged parallel to arm 41 said arm 43 being loosely mounted on the shaft 39. The front end 44 of arm 43 is fork-shaped and grips over a stud 45 arranged at the lower end of rod 26. The arm 41 of the bell-crank lever and also the arm 43 are enclosed by a clip or sleeve 46 shiftable on both arms together.

This clip 46 has laterally projecting studs 47 carried by a fork 48 at the free end of an arm 49 which is pivotably mounted on a pin 50. The arm 49 is operated by an eccentric 51, said eccentric having a bent arm 53 engaging a stud 52 of arm 49 (Fig. 2). The eccentric 51 is connected to the stop mechanism for the printing press, which is not illustrated in the drawing as it is of well known construction, and the eccentric is operated at the same time with this stop mechanism.

When sleeve 46 is on the arms 41 and 43 in the position shown in Fig. 2, these arms 15 are coupled with one another, so that at the upward movement of arm 41 under the action of roller 37 pushing against roller 40 of arm 38, the arm 43 is moved too, and rod 26 is raised. By this raising of rod 26 20 the foremost address printing plate 12 in the container 16 is lifted by means of hook 25 over the projection 24, the stops 29 being at the same time turned backwards, so that they will release that address printing plate 25 12 which has just before been used for printing, said plate then slipping down into the receiving container not shown. At the following downward oscillation of arm 41, which if desired may be effected by means 30 of a spring, the arm 43, coupled with arm 41 by the sleeve 46 when the latter is in the position shown in Fig. 2, will be moved in such a way that rod 26 is lowered and liberates the previously lifted foremost address 35 printing plate 12 of container 16, so that this plate will enter the guide path 10 and slip down in printing position before support 11, where it is securely held by the stops 29 which in the meantime have advanced 40 again under the action of spring 32.

When, however, the printing operation of the printing press is stopped in the well known manner, whilst the driving mechanism of the printing press continues to operate, the sleeve 46 is at the same time shifted by the eccentric 51 through the intermediary of arms 53 and 49 on the arms 41, 43 in such a manner that the sleeve 46 will assume the position shown in Fig. 6. 45 The tapered or stepped end 42 of arm 41 then can move idly up and down within the sleeve 46 without affecting the arm 43 loosely mounted on the shaft 39. The consequence will be that rod 26 and stops 29 will not 50 be operated during this time, so that no fresh address printing plates may come from container 16 into the guide path 10. By these means the conveying mechanism for the address printing plates is stopped simultaneously with and in dependence of stopping of the printing operation.

Numerous modifications of the form of construction shown are possible without departing from the scope of invention. Especially the shape and construction of the sev-

eral elements, and the manner in which they are operated, may be altered.

The mechanism for the feeding and delivering of the address printing plates may be used also in printing presses of other type, 70 for instance in fly-presses, and these presses also may be fitted with a stopping mechanism by the operation of which the address printing plates are to be retained at the same time.

Having now particularly described and ascertained the nature of my said invention, I declare that what I claim is:—

1. In an addressing device for printing presses for printing of fixed text with 80 changeable address, a container for the address printing plates supplied for printing, said container being arranged below the inking means for the inking rollers of the printing press and behind the printing plane of the press, the delivery opening of said container being arranged in the printing plane of the press, a guide path for the address printing plates below said delivery opening of said container, said guide path being inclined in such a degree to the horizontal direction that said address printing plates will slip along said guide path downward into printing position under the action of their own gravity.

2. In an addressing device for printing presses for printing of fixed text with changeable address, a container for the address printing plates supplied for printing, said container being arranged below the inking means for the inking rollers of the printing press and behind the printing plane of the press the delivery opening of said container being arranged laterally of the printing surface of the printing press serving for printing the fixed text, and close to the upper end of said printing surface, a guide path for the address printing plates below said delivery opening of said container and beside said printing surface, said guide path being inclined in such a degree to the horizontal direction that said address printing plates will slip along said guide path downward into printing position under the action of their own gravity and, a movable stop within said guide path below the printing position.

3. In an addressing device for printing presses for printing of fixed text with changeable address, a container for the address printing plates supplied for printing, said container being arranged below the inking means for the inking rollers of the printing press and behind the printing plane of the press the delivery opening of said container being arranged immediately above the printing surface of the printing press serving for printing the fixed text, a guide path for the address printing plates below said delivery opening of said container

- and beside said printing surface, said guide path being inclined in such a degree to the horizontal direction that said address printing plates will slip along said guide path downward into printing position under the action of their own gravity, a movable stop within said guide path below the printing position, said guide path being curved rearwardly below said printing position in such a manner that said address printing plates when released by said stop after printing will drop to the rear under the action of their own gravity.
4. In an addressing device for printing presses for printing of fixed text with changeable address, a container for the address printing plates supplied for printing, said container being arranged below the inking means for the inking rollers of the printing press and behind the printing plane of the press the delivery opening of said container being arranged in the printing plane of the press, a guide path for the address printing plates below said delivery opening of said container, said guide path being inclined in such a degree to the horizontal direction that said address printing plates will slip along said guide path downward into printing position under the action of their own gravity, a projection arranged at said delivery opening of said container for holding the foremost address printing plate within said container, a lifter for raising said foremost plate over said projection, means for moving said lifter up and down, said means being controlled by the actuating mechanism of the printing press.
5. In an addressing device for printing presses for printing of fixed text with changeable address, a container for the address printing plates supplied for printing, said container being arranged below the inking means for the inking rollers of the printing press and behind the printing plane of the press, the delivery opening of said container being arranged laterally of the printing surface of the printing press serving for printing the fixed text, and close to the upper end of said printing surface, a guide path for the address printing plates below said delivery opening of said container and beside said printing surface, said guide path being inclined in such a degree to the horizontal direction that said address printing plates will slip along said guide path downward into printing position under the action of their own gravity, a projection arranged at said delivery opening of said container for holding the foremost address printing plate within said container, a hook shaped lifter for raising said foremost plate over said projection, means for moving said hook shaped lifter up and down, said means being controlled by the actuating mechanism of the printing press.
6. In an addressing device for printing presses for printing of fixed text with changeable address, a container for the address printing plates supplied for printing, said container being arranged below the inking means for the inking rollers of the printing press and behind the printing plane of the press the delivery opening of said container being arranged laterally of the printing surface of the printing press serving for printing the fixed text, and close to the upper end of said printing surface, a guide path for the address printing plates below said delivery opening of said container and beside said printing surface, said guide path being inclined in such a degree to the horizontal direction that said address printing plates will slip along said guide path downward into printing position under the action of their own gravity, a projection arranged at said delivery opening of said container for holding the foremost address printing plate within said container, a hook shaped lifter for raising said foremost plate over said projection, means for moving said hook shaped lifter up and down, said means being controlled by the actuating mechanism of the printing press, and means for releasing said stop with the raising of said lifter.

8. In an addressing device for printing presses for printing of fixed text with changeable address, a container for the address printing plates supplied for printing, the delivery opening of said container being arranged laterally of the printing surface of the printing press serving for printing the fixed text, and close to the upper end of said printing surface, a guide path for the address printing plates below said delivery opening of said container and beside said printing surface, said guide path being inclined in such a degree to the horizontal direction that said address printing plates will slip along said guide path downward into printing position under the action of their own gravity, a movable stop within said guide path below the printing position, a projection arranged at said delivery opening of said container for holding the foremost address printing plate within said container, a lifter for raising said foremost plate over said projection, a rod for moving said lifter up and down, said rod being controlled by the actuating mechanism of the printing press, a projection on said rod, said projection coming into engagement with said stop when said rod is being raised.
9. In an addressing device for printing presses for printing of fixed text with changeable address, a container for the address printing plates supplied for printing, said container being arranged below the inking means for the inking rollers of the printing press and behind the printing plane of the press, the delivery opening of said container being arranged laterally of the printing surface of the printing press serving for printing the fixed text, and close to the upper end of said printing surface, a guide path for the address printing plates below said delivery opening of said container and beside said printing surface, said guide path being inclined in such a degree to the horizontal direction that said address printing plates will slip along said guide path downward into printing position under the action of their own gravity, a movable stop within said guide path below the printing position, said stop being formed by a double-armed lever, means for turning said lever, said means being controlled by the driving mechanism of the printing press.
10. In an addressing device for printing presses for printing of fixed text with changeable address, a container for the address printing plates supplied for printing, the delivery opening of said container being arranged laterally of the printing surface of the printing press serving for printing the fixed text, and close to the upper end of said printing surface, a guide path for the address printing plates below said delivery opening of said container and beside said printing surface, said guide path being inclined in such a degree to the horizontal direction that said address printing plates will slip along said guide path downward into printing position under the action of their own gravity, a movable stop within said guide path below the printing position, a projection arranged at said delivery opening of said container for holding the foremost address printing plate within said container, a lifter for raising said foremost plate over said projection, means for moving said lifter up and down, said means being controlled by the actuating mechanism of the printing press, an engaging and disengaging coupling arranged between said moving and said controlling means, means for disengaging said coupling when the printing press is being stopped.
11. In an addressing device for printing presses for printing of fixed text with changeable address, a container for the address printing plates supplied for printing, the delivery opening of said container being arranged laterally of the printing surface of the printing press serving for printing the fixed text, and close to the upper end of said printing surface, a guide path for the address printing plates below said delivery opening of said container and beside said printing surface, said guide path being inclined in such a degree to the horizontal direction that said address printing plates will slip along said guide path downward into printing position under the action of their own gravity, a projection arranged at said delivery opening of said container for holding the foremost address printing plate within said container, a lifter for raising said foremost plate over said projection, means for moving said lifter up and down, said means being controlled by the actuating mechanism of the printing press, an arm arranged to be moved by said actuating mechanism of the printing press, a second arm parallel to said first named arm, said second arm being loosely arranged, said second arm being connected with said lifter, a movable sleeve surrounding both said arms, means for connecting said sleeve with a stopping device for the printing press for uncoupling both said arms when the printing press is being stopped.
12. In an addressing device for printing presses for printing of fixed text with changeable address, a container for the address printing plates supplied for printing, said container being arranged below the inking means for the inking rollers of the printing press and behind the printing plane of the press, the delivery opening of said container being arranged in the printing plane of the press, a guide path for the address printing plates below said delivery opening of said container, said guide path being inclined in such a degree to the horizontal direction that said address printing plates will slip along said guide path downward into printing position under the action of their own gravity, a movable stop within said guide path below the printing position, a projection arranged at said delivery opening of said container for holding the foremost address printing plate within said container, a lifter for raising said foremost plate over said projection, means for moving said lifter up and down, said means being controlled by the actuating mechanism of the printing press, an engaging and disengaging coupling arranged between said moving and said controlling means, means for disengaging said coupling when the printing press is being stopped.

into printing position under the action of their own gravity, means for rigidly fastening said guide path with the parts belonging thereto on the bed of the printing surface in 5 a removable manner.

13. In an addressing device for printing presses for printing of fixed text with changeable address, a container for the address printing plates supplied for printing, 10 the delivery opening of said container being arranged laterally of the printing surface of the printing press serving for printing the fixed text, and close to the upper end of said printing surface, a guide path for the address printing plates below said delivery

opening of said container and beside said printing surface, said guide path being inclined in such a degree to the horizontal direction that said address printing plates will slip along said guide path downward into 20 printing position under the action of their own gravity, a movable stop within said guide path below the printing position, means for rocking said address printing plate which is just in printing position when 25 said stop is being released.

In testimony whereof I have hereunto set my hand.

HUGO TOCKHORN.
